UNITED STATES PATENT OFFICE

ABRAM MACMILLAN, OF CHICAGO, ILLINOIS

BUILDING CONSTRUCTION

Application filed March 2, 1929. Serial No. 343,880.

An object of this invention is to provide a floor construction wherein the stresses are reduced to a minimum for a given column spacing and for a given loading. This is accomplished in part by using arches arranged diagonally between columns, thereby reducing the effective sizes of the floor panels, and, at the same time, permitting the greatest spacing of the supporting columns.

Another object is to provide a floor construction in which substantially all the parts are in compression, thereby largely eliminating the necessity for steel reinforcement.

In accordance with the present invention, I have discarded the use of girders and have utilized the great load carrying properties of the arch and have disposed the columns of the building in such manner that the size of the floor panels between the load carrying arches is reduced to a minimum, whereby less metal reinforcement is required and less concrete is necessary to obtain the required strength and rigidity. Furthermore, in accordance with the present invention, all, or practically all, of the stresses are in compression, there being very little tensile stresses present because of the arch construction employed.

The invention consists, therefore, in a building construction in which the floor is carried by arches extending from one column to several columns. It further consists in a building construction wherein the arches extend from column to column along diagonal lines whereby the size of the panels between the column is greatly reduced. It further consists in a building construction in which the obliquely extending arches intersect one another midway between their supports, whereby the area of the panels is reduced to a minimum.

It further consists in the several novel features of construction, arrangement and combination of parts hereinafter fully set forth and claimed.

The invention is clearly illustrated in the drawings accompanying this specification in which—

Figure 1 is a view, partly in plan and partly in horizontal section, of a fragment of a

building construction embodying one form of the present invention;

Fig. 2 is a vertical section taken on the line 2—2 of Fig. 1;

Fig. 3 is a detail vertical section taken on line 3—3 of Figs. 1 and 2;

Fig. 4 is a view, partly in horizontal section and partly in under plan, of a slightly modified form of the invention;

Fig. 5 is a detail vertical section taken on the line 5—5 of Fig. 4;

Fig. 6 is a vertical section showing another modified form of the invention;

Fig. 7 is a vertical section taken on the line 7—7 of Fig. 6;

Fig. 8 is a view, partly in plan and partly in horizontal section, showing a third embodied form of the invention; and

Fig. 9 is a vertical section taken on the line 9—9 of Fig. 8.

Referring to said drawings, and first to Figs. 1 to 3, inclusive, which illustrate the preferred embodiment of the invention, the reference character 10 designates one of the walls of the building and 11 the supporting columns thereof. When the building is formed of reinforced concrete, the concrete columns are ordinarily provided with metal reinforcements 12, as is customary. The columns are arranged in rows, running lengthwise and crosswise of the building, as is usual, and are widely spaced apart, the customary spacing being from eighteen to twenty-four feet or thereabouts.

At the several floors of the building, the columns are connected by arched beams 13 herein generally referred to as arches which, as a preference, extend diagonally from column to column, as illustrated in Fig. 1, and intersect each other midway between the columns as at 14. When the building is formed of reinforced concrete, the concrete arches are reinforced by reinforcement rods 15 and 16 located adjacent the intrados and extrados of the arch and running longitudinally there-

of and substantially parallel with the intrados and extrados. Other reinforcement members, here shown in the form of stirrups, 17, are provided in the arches to counteract any shearing strains therein. The lon-

itudinal reinforcement rods extend through the columns and the lower reinforcement rods 16 and continued down beyond the curved ends of the intrados of the arches and are 5 anchored in the columns below the arches.

The floor 18 in the preferred form is in the nature of a flat slab of reinforced concrete integrally united with the columns and arches. The metal reinforcements of 10 the slab may comprise upper and lower reinforcement rods 19 and 20 which extend across the arches 13 and, preferably, are arranged at right angles to each other. As is customary, some of the reinforcement rods 15 19 may be bent down at points beyond the arches and continued adjacent the lower face of the floor.

It will be observed from an inspection of Fig. 1 that while the columns 11 are widely 20 spaced, the panels *p* (defined by the spaces between the obliquely extending intersecting arches) are of considerably less length and width than the distance between the columns, and, consequently, there is a great saving in 25 the amount of reinforcement required as well as the thickness of the floor slab. Furthermore, by reason of the arch construction, there is more free head room underneath the bottom of the floor than in buildings 30 where girders are employed.

Furthermore, practically all of the stresses are in compression which makes it advantageous to employ reinforced concrete in the construction of buildings, since concrete has 35 a maximum efficiency for resisting compression stresses. Inasmuch as the floors are likely to be loaded unevenly, the longitudinal reinforcement rods are provided in the arches to take care of any tensile stresses that 40 may occur, and this is particularly true, since part of the floor on one side of a column may be heavily loaded, whereas the part on the opposite side thereof may not be loaded, and, consequently, the strain is transmitted from 45 the floor on one side of the column to the part on the other side thereof.

In the form of the invention illustrated in Figs. 4 and 5, the intersecting arches 13^x are employed, as in the preferred form, but in 50 place of the flat plate floor slab construction, a thin slab 18^x is employed which is reinforced by girder-like members 18^z which divide each floor panel into smaller panels. The girders are reinforced by metal reinforcing rods 19^x and 20^x, as is customary.

In the form of the invention illustrated in Figs. 6 and 7, the construction is substantially the same as that of the preferred form, except that the arches 13^a in part are spaced 60 from the floor slab. The arches merge into the floor slab 18^a at the places where they intersect each other, and are also connected to the floor slab by upright webs 13^b which are thinner than the arches. When made of reinforced concrete, the columns, floors, slabs and

70 arches are reinforced by suitable reinforcement rods disposed in the concrete body substantially as described in connection with the preferred form of the invention, except that the arches have the longitudinal reinforcement rods 16^a paralleling the intrados and extrados therof, and other reinforced rods 15^b are placed in the floor slab over the arches and near the upper side of the floor slab. The floor reinforcement rods are shown at 75 19^a and 19^b.

In the modified form illustrated in Figs. 8 and 9, the arches 13^c extend diagonally between the columns 11^c, but in one direction only, thereby reducing the width of the 80 panels between the arches to a minimum. The columns and arches are metal reinforced as in the preferred form. In this case, the floor slab may be of ribbed type wherein the reinforcement rods are placed adjacent the 85 upper and lower sides of the ribs 18^d, as well as throughout the floor slab itself.

It will be understood that in constructing 90 reinforced concrete buildings, containing the invention herein described, suitable forms are employed for giving shape to the columns, arches and floor slabs, and that the reinforcement rods are put in place in the forms and the concrete poured around the reinforcement rods in the usual manner. When the 95 ribbed floor slab construction is employed, inverted pans may be used for shaping the lower face of the floor slab.

From the above, it is apparent that the 100 columns may be widely spaced, and because of the utilization of the load carrying properties of the arches, especially when arranged diagonally of the building, the size of the floor panels is materially reduced, thereby 105 making it possible to employ a minimum amount of metal reinforcement for the concrete in the entire construction. By using any of the arrangements of arches and floor 110 illustrated, and carefully calculating the arch and floor dimensions, it is possible to make a floor construction in which substantially all the parts are in compression when there is substantially a uniformly distributed load on the floor.

Furthermore, by supporting the floor slab 115 on arches extending diagonally from column to column, the load is first transferred to the arches and by them to the columns. The purpose of this is, first, to transfer the floor loads to the columns in a manner requiring the least material and which produces the least possible stresses; second, to have a type of construction whose stresses can be calculated definitely, which is not true of a flat slab, because the stresses therein are indeterminate and the method employed in calculating the same are largely empirical because of the highly complicated character of the 120 stresses which do not permit of accurate mathematical statement; third, to have a 125 130

structure which is more rigid than a flat slab and when wind stresses must be considered, they can be definitely calculated and provided for more effectively; and, fourth, to have a 5 type of construction which will better resist vibrations resulting from operation of heavy machinery.

The term "arched beams", as used in the specification and claims, is meant to include 10 beams of either constant or varying cross-section, unless otherwise limited.

I claim:

1. A monolithic building construction comprising in combination spaced floors, 15 supporting columns arranged in repeated spaced relation between the floors and extending from floor to floor, floor carrying arched beams extending continuously from column to column at each of the floors, and 20 a floor slab carried directly by said arched beams.

2. A monolithic building construction comprising in combination spaced floors, supporting columns arranged in repeated spaced relation 25 between the floors and extending from floor to floor, floor carrying arched beams extending from column to column at each of the floors, certain of said arched beams being arranged transversely of the others and defining panels of less area than the areas between the adjacent columns, and a floor slab carried by said arched beams.

3. A monolithic building construction comprising in combination spaced floors, supporting 35 columns arranged in repeated spaced relation between the floors and extending from floor to floor, obliquely extending intersecting arched beams extending from column to column at each of the floors and defining panels of less area than the area between adjacent columns, and a floor slab carried by said arched beams.

4. A monolithic building construction comprising in combination spaced floors, reinforced concrete supporting columns arranged in repeated spaced relation between the floors and extending from floor to floor, reinforced concrete floor supporting arched beams extending obliquely from column to 50 column at each of the floors, there being longitudinally extending metal reinforcements adjacent the intrados and extrados of the arched beams, and a reinforced concrete floor slab carried by said arched beams, the columns, arched beams and floor slab being integrally united.

5. A monolithic building construction comprising in combination spaced floors, supporting columns arranged in repeated spaced 60 relation between the floors and extending from floor to floor, floor carrying arched beams extending from column to column at each of the floors, and a floor slab carried directly by said arched beams and comprising 65 the upper parts of the arched beams, said

columns, arched beams and floor slab being composed of reinforced concrete and the arched beams being proportioned to translate vertical pressure into compression stresses running in a direction generally lengthwise of the arched beams. 70

6. A monolithic building construction comprising repeated series of spaced supporting columns arranged within the confines of the building and extending from floor to floor thereof, intersecting arched beams extending continuously between pairs of columns at each of the floors and defining panels of less width than the distance between adjacent columns, a floor slab carried directly by the beams for uniformly distributing the vertical stresses of the slab through the arched beams to the columns. 75

7. A monolithic building construction comprising repeated series of spaced supporting columns arranged within the confines of the building and extending from floor to floor thereof, intersecting reinforced arched beams extending continuously between pairs of columns at each of the floors, each of said beams characterized by a vertically extending web, a floor slab carried directly by the webbed beams for uniformly distributing the vertical stresses of the slab through arched beams and webs to the columns. 80

In testimony whereof, I have hereunto set my hand and affixed my seal this 28th day of February, 1929.
